UNITED STATES PATENT OFFICE

STANLEY E. SLOSS, OF LOUISVILLE, KENTUCKY

MANTEL

Application filed February 26, 1930. Serial No. 431,502.

The present invention relates to mantels, and more particularly to a mantel construction embodying a fireplace and hearth, which may be set up as a unit without the necessity 5 of connecting same to a chimney or in any manner preparing the wall against which the unit is placed.

Such a mantel may be built to imitate the customary type of built-in mantel and fireplace, which ordinarily combines a frame of 10 wooden columns, and shelf with a facing, body or both of tile, brick, stone, marble, or the like, but the mantel forming the subject matter of this invention will preferably have 15 a facing, hearth, back hearth and fireplace in imitation of tile, brick, stone or marble made by stamping a metal sheet and finishing same in any desired manner to represent or imitate the above named conventional facings and 20 bodies.

One of the objects of the present invention is to provide a mantel which may be formed of several elements completely assembled in a single unit ready for installation, or which may, if desired, be formed as 25 an integral unit, and in which no chimney breast or other extension in the wall is necessary. Such a mantel can be set or fastened to any flat wall without previous preparation.

Another object of the present invention is to provide a mantel and fireplace combination which may be readily combined with heat appliances of gas, oil or electricity.

A further object is to provide a mantel 35 which can be manufactured and shipped as a complete unit or which may be made of a minimum number of elements easily assembled into a completed unit upon its installation.

To the attainment of these and other objects which will appear as the description proceeds, reference is made to the accompanying drawings in which like parts are 45 designated by like reference numerals.

In the drawings:—

Fig. 1 represents a front elevation of the assembled unit;

Fig. 2 is a section on line 2—2 of Fig. 1;

Fig. 3 is a section on line 3—3 of Fig. 1;

Fig. 4 is a detailed section of one corner of the unit;

Fig. 5 is a section on line 5—5 of Fig. 4; and

Fig. 6 is the section on line 6—6 of Fig. 2. 55
Referring to the drawings, it will be noted that a preferred unit is built-up of not more than nine structural elements, same being the front facing indicated generally at 10, and which facing simulates a lintel, and the front 60 ends of the jambs or coverings of the fireplace, a pair of front corner posts 11, the shelf of the mantel 12 having a pair of candle sticks 13 forming in effect a continuation of the corner posts above the shelf. 65

A hearth 14 merges into a fireplace having jambs or covings 15 and a back 16, it being noted that the covings and back wall are preferably formed by one piece of sheet metal bent to shape. 70

A curved or tapered top portion 17 for the fireplace completes the unit, this portion 17 extending from the top of the jambs and back and gradually tapering forwardly to the top of the fireplace opening formed in 75 the facing 10. When the several portions are assembled, the mantel shelf 12 and the corner posts 11 will form a frame extending up each side of the unit and across the top thereof.

While in most installations the unit is designed for use with electric, gas, or oil burning apparatus and accordingly no connection with a flue or chimney is necessary, it will be obvious that a slot or throat might be formed behind the facing 10, in the portion 17, as 80 such a throat need not exceed four inches in width, and suitable connection to a chimney could be made therefrom. 85

Furthermore, the jambs 15 need not extend straight back, but might be splayed or disposed angularly with respect to the back 16 in order to throw out more heat, if desired. 90

The several sections are preferably formed of stamped metal with the exception of the corner posts 11 and the ornamental shelf 12 95 which may be made of any desired material, but usually of wood. The several metal sections will be attached to each other by flanges 18 and bolts 19 extending therethrough, and the corner posts of wood may have a pie- 100

shaped wedge cut therefrom, in order to permit of a fit about the angle of the front facing 10 which has side flanges 20 extending rearwardly.

5 By reference to Figs. 2 and 3, it will be noted that the unit when assembled may be set against a wall without any previous preparation thereof, inasmuch as no chimney breast or other extension in the wall is necessary. The side flanges or wings 20 will be cut out at the base thereof to fit the baseboard, molding and shoe, and to closely engage the wall proper thereabove.

The candles 13 may be of any general nature, but desirably they will be detachable from the mantel and will be provided with prongs 21 forming an electric connector and will fit into the socket 22 in which are mounted the terminals of an electric conductor 23.

30 Suitable connections from the prongs 21 through the candle will provide current for a lamp 24.

Whether the candle stick 13 is equipped for electric lighting or not, the prongs 21 will 25 act as a means of detachably mounting the candle stick in the mantel piece.

By the combination of elements as above set forth an extremely useful and highly ornamental unit is had; the combination of 30 a wooden frame formed by the shelf and corner posts to fit over an imitation tile or marble facing provides not only strength in a unit of this character, but the shelf may be curved to match the top of the columns which 35 in turn may be hand-turned to produce an ornamental appearance, and the shelf may swell out forwardly in the center to produce unusual lines in a mantel construction. A control switch for the electric candles and 40 suitable wiring may be placed on the underside of the shelf 12 if desired, instead of extending through the corner post.

As stated above while the unit is primarily designed for use with a room heater of the 45 gas, electric or oil type, and no preparation of the wall is necessary, by very slight adaptation the unit may be converted into a fireplace suitable for connection to a chimney.

Having thus described my invention, what 50 I claim as new and desire to secure by Letters Patent of the United States is:—

1. A portable combined mantel, fireplace and hearth unit, comprising a three-piece outer framework consisting of a mantel shelf 55 having corner posts extending therefrom, and a fireplace structure within said frame consisting of a hearth section, vertical wall sections, a top wall section and a front facing section extending from said wall sections to 60 said frame and detachably connecting said wall sections to said frame, said facing having wings extending rearwardly to form the ends of the structure, said wings having recessed portions engageable with the baseboard of a conventional unprepared wall 65

and edge portions engageable with such wall above the baseboard, and said shelf having an edge portion engageable with said wall.

2. An article of the class described comprising a mantel shelf having corner posts 70 extending therefrom and forming an exposed frame therewith, and a fireplace within said frame formed of metal sections detachably secured together and a facing section attached to said frame and to said fireplace thereby to connect said fireplace and frame, said facing having wings extending rearwardly to form the ends of the structure, all of said elements being combined and connected to form a single unit, said wings being 75 recessed to fit the baseboard of a conventional wall and having edge portions engageable with such wall above the baseboard.

3. An article of the class described comprising a mantel shelf having corner posts 80 extending therefrom and forming an exposed frame therewith and a fireplace within said frame formed of metal sections detachably secured together and a facing section 85 attached to said frame and to said fireplace thereby to connect said fireplace and frame, said facing having wings extending rearwardly to form the ends of the structure, a detachable candlestick mounted on said 90 shelf and forming in effect an upstanding extension of one of said corner posts and having projections extending through said shelf and into said post, all of said elements being combined and connected to form a single unit.

4. An article of the class described comprising a mantel shelf having corner posts 95 extending therefrom and forming an exposed frame therewith and a fireplace within said frame formed of metal sections detachably secured together, one of said sections forming a back wall of the fireplace, and another of said sections forming a facing attached to said frame and to said fireplace thereby 100 to connect said fireplace and frame, said facing having wings extending rearwardly to form the ends of the structure, the rear edges of said wings and the rear edge of 105 said shelf being adapted to engage a conventional unprepared wall and said rear wall section of the fireplace being spaced forwardly of the said rear edge sections, all of said elements being combined and connected to form a single unit.

In testimony whereof I hereunto affix my signature.

STANLEY E. SLOSS.
